UNITED STATES PATENT OFFICE.

VINCENT GROBY APPLE, OF DAYTON, OHIO, ASSIGNOR TO THE APPLE ELECTRIC COMPANY, OF DAYTON, OHIO, A CORPORATION OF OHIO.

DYNAMO-ELECTRIC MACHINE.

1,081,084.

Specification of Letters Patent.

Patented Dec. 9, 1913.

Application filed November 27, 1908. Serial No. 464,522.

To all whom it may concern:

Be it known that I, VINCENT G. APPLE, a citizen of the United States, residing at Dayton, in the county of Montgomery and State of Ohio, have invented certain new and useful Improvements in Dynamo-Electric Machines, of which the following is a specification.

My invention relates to improvements in 10 dynamo electric machines, and in many of its features is applicable to either generators or motors, but it applies especially in some of its features to self-governed electrical generators of small size, such as are 15 commonly employed for the generation of electric current for gas engine ignition systems, and like uses.

Among the general objects of my invention are to provide a dynamo electric 20 machine of small size, adapted for economical construction, ease in assembling and durability, designed to produce a relatively great output of current in proportion to its dimensions.

25 Other and further objects of my invention will become apparent to those skilled in the art from the following description taken in conjunction with the accompanying drawings, wherein I have illustrated a horizontal 30 longitudinal section of an embodiment of my invention.

In the preferred embodiment of my invention shown I provide a multipolar dynamo, whereof 10 is the frame, preferably a casting, 35 shaped as a field ring, and provided with integral interior projections which constitute the field cores, and whereof a suitable number, preferably four, are provided. One end of the frame 10 is reduced to an integral 40 throat 13, axially unobstructed, and of size slightly larger than the armature intended for the machine. The other end of the cast frame 10 is provided with an end opening, preferably the full diameter of the field ring, 45 and is provided with an edge recess for receiving a cap or door 15, which is preferably a drawn sheet metal cup of exterior diameter corresponding with that of frame 10. The cup or door 15 is preferably connected with 50 the frame on each side by a hinging latch construction, generally indicated at 16, each in the form of a strap hinge, whereof the two relatively movable members 17 and 18 are connected by a detachable pintle, or pin 55 19, so that each hinge constitutes a latch

or fastening. Obviously either pin may be withdrawn to permit the door to open either to the right hand or to the left, or both pins may be withdrawn to permit the removal of the door.

60 The end of the frame 10 proximate to the door is bridged by an integral supporting member or spider 21 shaped to provide a commutator space beyond the edge of the end opening, for accessibility, and arranged 65 to support the commutator brushes and the armature shaft. Specifically such spider provides feet 22 converging from opposite sides of the frame at its end until separated only by a convenient commutator space, and 70 thence extending rearwardly, as at 23, in longitudinal parallelism, but transversely with a curvature to conform to the commutator space, to a point sufficiently remote from the end of the frame proper where 75 the sides 23 are connected by an end wall 24 centrally thickened to form an integral boss 25. This integral boss 25 affords support for the armature shaft and governor 80 spring, and the sides receive the brush holders and afford convenient space for the connection of the electrical binding posts. The shaft, 26, has its inner end supported in and projecting through a bushing 27, supported in the boss 25, and carries the commutator 28 and 85 the armature 29, the former being disposed in the armature space bounded by the spider structure 21, and the latter being arranged within the body of the frame, under the influence of the field. The armature structure, field magnets and commutator may be 90 of any suitable construction as the details thereof form no part of my present invention.

95 Any of the well known types of commutator brushes may be used.

The side walls of the extension 21 carry insulated binding posts 33 to which are suitably wired the commutator brushes and the field coil, exterior wiring connections being 100 made as required, through apertures 39 in the sides of the rigid frame 10. The throat 13 of the frame is provided with a closure or head 40, having an inturned rim, to interfit in the throat, and a central boss 42 in 105 which is fixed a bearing sleeve 43, for the outer end of the shaft 26, preferably extending inward beyond the head.

110 While I have herein described in some detail a specific embodiment of my invention,

the construction of which I believe to be new and advantageous in many details, it will be apparent that many changes in the specific construction might be made without 5 departure from the spirit and scope of my invention, within the scope of the appended claim.

Having described my invention, what I claim is.

10 In a dynamo electric machine, a single piece frame comprising a pole ring and a spider projecting beyond one end of said pole ring, shaped to receive within it the commutator in position projecting beyond 15 an edge of the pole ring for accessibility,

and to afford support to the commutator brushes, a hinged cap closure overlying said spider and commutator, said frame having at its other end an opening through which the armature and commutator may be inserted, and a detachable closure for the driving end of the frame supporting a shaft bearing for the armature shaft. 20

In testimony whereof I hereunto set my hand in the presence of two witnesses.

VINCENT GROBY APPLE.
